UNITED STATES PATENT OFFICE.

GEORGE FRED BLUME, OF PHILADELPHIA, PENNSYLVANIA.

DISTANCING DEVICE.

1,380,347.

Specification of Letters Patent. Patented June 7, 1921.

Application filed January 13, 1921. Serial No. 436,967.

To all whom it may concern:

Be it known that I, GEORGE FRED BLUME, a citizen of the United States, residing at Philadelphia, in the county of Philadelphia, 5 and State of Pennsylvania, have invented a new and useful Distancing Device, of which the following is a specification.

This invention relates to motor or engine supports, and more particularly to a novel 10 means for distancing the motor base with respect to its foundation, whereby the motor will be maintained in its proper position.

The object of the invention is to provide a support of this character which may be 15 forced into its proper supporting position, means being provided for anchoring the movable elements of the device, in their positions of adjustment.

Another object of the invention is to provide 20 an improved method of adjusting a motor base with respect to its foundation, the method including a securing step, whereby the motor will be maintained in a predetermined position.

With the foregoing and other objects in 25 view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawings:—

Figure 1 illustrates a sectional view through an adjusting device constructed in accordance with the present invention.

Fig. 2 is a sectional view taken at right 40 angles to Fig. 1.

Referring to the drawing in detail, the reference character 5 designates a base of an engine, motor or the like which is to be positioned and secured to its foundation, 45 which in the present showing is indicated by the reference character 6 and has a plurality of bolts such as indicated at 7, secured in the foundation, the bolts being of lengths to extend through suitable openings 50 in the base 5.

The distancing device includes an upper plate 8 which is provided with an upper relatively straight surface, and a lower convex surface 9, the convex surface 9 being 55 signed to be positioned in the concaved up-

per surface of the central plate 10, the undersurface of the plate 10 being inclined as indicated at 11 to coöperate with the upper inclined edge of the wedge member 12. The plates 8 and 9 are provided with suitable 60 openings to accommodate the bolts 7, while the wedge member 12 is provided with an elongated opening to accommodate the bolt 7, and permit of movement of the wedge member with respect to the bolt 7. 65

Thus it will be seen that due to the concaved surface of the plate 10 and the convex surface of the plate 8, the plates 8 and 10 are secured with respect to each other.

Grooves are formed in the plates 8 and 9, 70 the grooves being disposed along the outer edges thereof, and at points in proximity to the adjacent plate, which grooves are provided for the purpose of receiving a suitable welded material indicated at 13 so that 75 the adjacent plates and wedge member 12 may be welded together to eliminate movement of one member with respect to the other, and consequently insure against movement of the engine base. 80

When the wedge member 12 has been moved to its proper position, it is to be understood that the nut 14 is moved to cause the same to bind on the upper surface of the base 5 to strengthen the connection between 85 the members.

In carrying out the method, the plates 8 and 9 are positioned under the base 5, the wedge member 12 being positioned over the bolt 7. With the members in this position, 90 the wedge member 12 is driven to its proper position to level the engine base 5, and material is welded in the grooves of the plates.

Having thus described the invention, what is claimed as new is:—

1. In combination with a foundation and engine base, a distancing device including a pair of plates, one of said plates having a concaved surface, the other plate having a convex surface positioned within the 100 concaved surface, one of said plates having an inclined lower surface, a wedge member coöperating with the inclined surface for moving the plates vertically, and means for securing the plates and wedge against movement. 105

2. In combination with a foundation and engine base, a pair of plates, each of said plates having cut out portions formed in the edges, a wedge member operating un- 110

der the plates for moving the plates vertically, means for securing the plates and wedge member together, and means disposed within the cut out portions for locking the plates and wedge member against movement.

In testimony that I claim the foregoing

as my own, I have hereto affixed my signature in the presence of two witnesses.

GEORGE FRED BLUME.
